FISH LURE

Earl E. Miller, Dowagiac, Mich., assignor to James Heddon's Sons, Dowagiac, Mich., a corporation of Michigan

Filed Oct. 19, 1959, Ser. No. 57,968

Term of patent 14 years

(Cl. D31—4)

Fig. 1

Fig. 2

Fig. 3

Fig. 4

The dominant features of the fish lure reside in the portions shown in solid lines.

I claim:

The ornamental design for a fish lure, as shown and described.
